UNITED STATES PATENT OFFICE.

CHRISTOPHER McCLAY, OF OREGON CITY, OREGON.

AUTOMOBILE LIGHT.

Application filed February 21, 1925. Serial No. 10,771.

To all whom it may concern:

Be it known that I, CHRISTOPHER McCLAY, a citizen of the United States, residing at Oregon City, in the county of Clackamas 5 and State of Oregon, have invented a new and useful Automobile Light, of which the following is a specification.

My invention relates to automobile lights in which the direct rays from an electric 10 light bulb are partly thrown against a deflecting hood and partly sent through a colored glass plate whereby that part of the rays is softened.

The main object of my invention is to 15 produce an illuminating device especially valuable for automobiles in order to avoid the dazzling glare which is so annoying to the oncoming motorist, and which is such a frequent source of disastrous accidents. A 20 further object is to produce spots of concentrated light in the general field of illumination.

Other objects and advantages are to be 25 found in the construction and arrangement of parts as will be described in the specification, and particularly pointed out in the appended claim.

I attain these objects with the mechanism 30 illustrated in the accompanying drawing, in which—

Fig. 1 is a front view of the entire apparatus.

Fig. 2 is a vertical cross section through the center line of Fig. 1.

Similar numerals refer to similar parts throughout the several views.

An electric light bulb 1 of standard construction is inserted in the customary socket 2, said socket 2 being connected by the electric wires 3 with a suitable electric source. It will be noticed that the longitudinal axis of the socket 2 points upward at an approximate angle of forty-five degrees. Proceeding from the socket 2 is a cup-shaped reflector 4 whose rim is covered by a lens 5. Joining the cup-shaped reflector 4 is a conical reflector 6, which encircles the edge of the former with a flange 7 and is held in place by the screws 8. This flange 7 is provided with an inwardly extending shoulder 9 to hold the lens 5 in place. The edge of the outwardly flaring wall of the conical reflector 6 is joined to a hood 10 whose top inclines toward and finally meets the longi-

tudinal axis of the socket 2. The open face 55 of the hood 10 is closed by a front lens 11 which may be fastened to the hood 10 in any desired manner. In front view the lens 11 should preferably appear as a circle. A spot in the upper part of the hood 10 is either 60 flattened or better yet, curved, as shown, to act as a concentrating mirror 12. Resting on the bottom of the conical reflector 6, and traversing the path of the lower half of the rays from the light bulb 1 is a vertically disposed colored glass plate 13, which extends upward to about the longitudinal axis of the socket. The manner of affixing the colored glass plate 13 in its place may be left to the choice of the trained mechanic. 70 A suitable casing 14 as indicated by the dotted lines, may be employed to enclose the construction, of course, with the exception of the front lens.

In this manner the reflected light from 75 the hood will be thrown from seventy-five to one hundred feet ahead, but containing only reflected light mingled with the rays from the colored glass, preferably green,—no dazzling glare can be experienced. A small 80 circle of brighter illumination will be produced by the concentrating mirror for a distance of about twenty-five or thirty feet where an automobile driver needs greatest clarity, yet this brighter spot also will be 85 without any dazzling glare.

Having thus described my invention, it will be seen that my objects have been accomplished, and, though I have shown the preferred form of construction, I reserve to 90 myself the right to make minor changes, providing I do not violate the spirit and principle of my invention.

I claim:

In an automobile light, the combination 95 of a cup-shaped reflector, an electric light bulb at the bottom of said cup-shaped reflector, the longitudinal axis of said cup-shaped reflector extending upward at an angle, a flange sliding over the outer edge 100 of said cup-shaped reflector, screws holding the flange to said cup-shaped reflector, an inwardly extending shoulder connected with the flange, a lens covering the opening of said cup-shaped reflector and held in place 105 by said shoulder, an outwardly flaring conical reflector proceeding from the flange, a hood firmly attached to the edge of the

conical reflector, the top of said hood inclining toward and meeting the longitudinal axis of the cup-shaped reflector, a portion in the top of said hood being pressed into a 5 concentrating mirror, a front lens covering the opening of said hood, a colored glass plate attached to the bottom of the conical

reflector and extending across the lower opening of said hood, and a casing surrounding the cup-shaped reflector including 10 the hood.

Signed by me at Portland, Oregon, this 14th day of February, 1925.

CHRISTOPHER McCLAY.
